UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed April 2, 1925. Serial No. 20,061.

- This invention relates to duplex or superposed platen-devices for typewriting machines, and to means for selectively moving the platen into or out of typing position.
- 5 One of the features of this invention is to facilitate the handling of manifold webs or sheets, especially where certain portions of the typed matter are to be omitted from one or more of the carbon-copies thereof.
- 10 In Patent No. 1,350,681 to Stickney et al. are shown two revolute platens, one surmounting the other; the pack of work-sheets being split into two sets, those in one set going over only one of said platens, and those 15 in both sets going over the other of said platens; whereby matter typed or manifolded upon the sheets in the first set does not appear upon the sheets in the other set. The structure disclosed in said patent necessi- 20 tates a reconstruction of the platen-frame and carriage of the Underwood typewriting machine; and one of the objects of the present invention is to simplify the mechanism, particularly with a view to compacting the 25 same by reducing the amount of room that is occupied by the platens; this being done with a view to mounting two platens in a standard Underwood typewriting machine, in place of the single platen usually em- 30 ployed therein. To this and other ends, one of the main features of the present improve- 35 ments resides in the provision of two platens, each consisting of a bar, which may be of metal with or without suitable leather or 40 other facing; these bar-platens being mounted one above the other and being shiftable to bring either one to typing position, and the other one out of typing position. Upon 45 one of the platens all of the work-sheets may be manifolded, while upon the other platen only certain of said sheets are typed, for the purposes set forth in said patent. Said bar- 50 platens are mounted upon arms whereby they are loosely supported upon the platen- 55 axle, which is usually provided in said Underwood machine, the arms not revolving with the axle; and the faces of said platens have a cylindrical curvature agreeing with that of the usual Underwood platen, so that 60 it becomes practicable to remove the ordinary platen and substitute these duplex or superposed platens in the same machine. Line-feeding of the work-sheet may be ef- 65 fected by one or more pairs of rolls, which 70 may occupy positions under the platens, to 75 receive the work-sheets as they are thrust down at the rear over the usual paper-shelf, and feed them forwardly and upwardly around one or both of said platens. The 80 feed-rolls may be driven by gearing, pref- 85 erably comprising pinions upon the feed- roll axles and an internal gear mounted upon the platen-axle, to be driven by the line- 90 space lever usually employed in said Under- 95 wood machine.
- Preferably the lower platen is independ- 100 ently swingable backwardly away from typ- 105 ing position, to permit the upper platen to swing down into typing position. This makes for compactness of the mechanism, 110 and particularly affords room within the confines of the standard machine for the feed-rolls below the platen. The work-sheet is inserted in the machine in a pack, and is fed between feed-rolls, and then is passed over one of the platens and separated, so that only the upper sheet will pass over the upper platen.
- Certain features relate to the compactness 115 of the device, and to the easy assembly 120 thereof. The device may preferably be built as a unit, and mounted on the platen-frame of the machine after removing the regular platen therefrom. The work-sheet is line- 125 fed by the same means normally controlling the work-sheet in the machine. The trans- 130 position of the platens is accomplished by means of a special hand-lever which may 135 form part of the unit.
- The work-sheets, interleaved with car- 140 bons, are inserted at the rear of the machine and passed down over a rear table. Then the leading edges of the sheets are engaged 145 by the feed-rolls. The entire assembly of work-sheets may be passed over the lower 150 platen, which normally may be at the print- 155 ing line, and one or more of the sheets are then separated from the rest, and are passed idly behind the upper platen. The outer 160 sheet or sheets overlie the upper platen.
- Normally, the lower platen receives the 165 printing upon the assembled sheets, but when for any reason it is desired to type certain 170 data upon the outer sheet or sheets only, then, by means of a lever the two platens are moved relatively to each other or trans- 175 posed, the lower one into idle position, and the upper one into typing position. Prefer- 180 ably the lower platen is moved inwardly or 185 backwardly to idle position, while the upper 190

platen is lowered to the printing line, the sheets, however, not being shifted at this time.

The transposing means may comprise two interlocking bail-pieces forming the platen-devices, and both platen-devices may be operatively connected by means of a cam-slot-and-pin arrangement, whereby the cam-slots in one of the platen-devices will control the movement of the other platen-device upon which the pins are fast.

The driving feed-rolls are operatively connected to both the line-space mechanism of the machine and to finger-wheels at the ends 15 of a controlling shaft, which substitutes the platen-shaft of the machine. Upon said shaft there is mounted an internal gear, fast thereto, and said gear engages pinions fast to the driving feed-rolls, in such a manner 20 that when the controlling shaft is rotated, either by the hand-wheels at the ends thereof, or by the regular line-space mechanism of the machine, the driving feed-rolls will also be rotated to feed the work-sheet to the 25 platens.

Other features and advantages will hereinafter appear.

In the accompanying drawings,

Figure 1 is a cross-sectional view, in elevation, through the center of the platen-frame of an Underwood typewriting machine, showing the two platens in their normal positions.

Figure 2 is a cross-sectional view, in elevation, showing the feed-roll releasing mechanism and the feed-roll driving mechanism.

Figure 3 is a cross-sectional view, in elevation, showing the upper platen lowered to the printing line.

Figure 4 is a detail showing the upper platen and the operating handle therefor.

Figure 5 is a detail showing the lower platen.

Figure 6 is a front view, in elevation, showing the device as applied to an Underwood typewriting machine.

Figure 7 is a top or plan view of the device, as applied to an Underwood typewriting machine.

A work-sheet, which may, for example, comprise an invoice-sheet 10 and a record-sheet 11, interleaved by a sheet of carbon-paper 12, is inserted, leading edge first, over a rear table 13, and down to be engaged by the regular feed-rolls 14 and 15, which cooperate respectively with driving feed-rolls 16 and 17. The assembled work-sheet is then passed over a platen 18, and the ledger-sheet, together with the carbon-paper, is led behind a second platen 19, which lies slightly above the platen 18, as shown in Figure 1. The statement-sheet is passed over the platen 19 and under the paper-fingers 20 of the machine. Then the assembled work-sheet is fed to typing position, whereupon the statement-

sheet is typed by means of type-bars 21, and through the interleaving sheet of carbon-paper the typing is copied upon the ledger-sheet.

The driving feed-rolls 16 and 17 are operatively connected to the line-spacing mechanism of the machine by means of the platen-shaft 22, upon which there is mounted an internal gear 23 fast thereto by means of a screw 27 threaded into a collar 26, forming an integral part of said gear which meshes with pinions 24, fast to shafts 25, upon which the rolls are mounted. The shafts 25 are journaled in side plates 26, and are laterally located by the pinion-collars 24^a and set-collars 27. The plates 26 are fast to the regular platen-frames 28 by means of screws 29, which may fit into the tapped holes normally supporting the platen-frame guard which is removed.

In order that the plates 26 may be more securely held, and at the same time to facilitate the easy removal thereof, there are provided end pieces 30 fast to the plates, and engaging the feed-roll shaft 31 to which the plates are secured by means of screws 32.

When, for any reason it is desired to type upon the statement-sheet only, the lower platen 18 is caused to recede to the rear, while the upper platen 19 is lowered to the printing point, as shown in Figure 3. To cause the transposition of the two platens, a lever 33, rockably mounted upon the shaft 22, is moved forwardly by means of a handle 34, thus causing the lever to move the lower platen by means of pins 35, engaging cam-grooves 36 cut into end plates 37, upon which the upper platen is rockably mounted. Due to the peculiar shape of the cam-grooves, when the lever is moved it will draw the lower platen 18 to the rear, while simultaneously the upper platen 19 is being lowered to the printing line. The lower platen is rockably mounted upon supporting studs 38 fast to the plates 26, and is designed in the form of a bail-piece having the end arms 39 fast to the platen and preferably forming an integral part thereof.

For the purpose of controlling the movement of the two platens relatively to each other, there is provided a spring 40, fast to the plates 26 by means of screws 41. Said spring 40 engages with a pin 42 fast to the lever 33, and, due to the peculiar shape of the spring 40 which forms a high point 43 corresponding to the neutral positions of the two platens, tends to force and to hold the pin 42 on either side of the high point 43. To limit the travel of the arm 33 outwardly, or away from the spring, there are provided two pins 44 fast to the plates 26, which pins determine the travel of the arm 33, as shown in Figures 1 and 3.

In order that this device may be handled as a unit when off the machine, and in order

to facilitate the placing of the device in the machine after removing the regular platen therefrom, the end plates 26 are fastened together by means of a cross-plate 45, which is secured to the plates by fasteners 46. Said plate 45 serves also as means to guide the work-sheet when the same is introduced in the machine, and is provided with a bent edge 47, to facilitate the back-feeding of the work-sheet. Another reinforcing element to hold the two end plates together, is provided in the form of a front table 48 at the delivery side of the platen. Said front table extends from one end plate to the other, and is fast thereto by means of fasteners 49. One of the functions of this table is to serve as a backing for the work-sheet, and is provided with a rounded edge 50 at the top thereof to stiffen the table, and 20 to afford a better surface for the work-sheet.

The feed-rolls 14 and 15 are releasable in the usual manner by means of a rockably mounted finger-piece 51, actuating upon a downwardly-extending link 52, which link 25 is, in turn, operatively connected to cross-shaft 53. When the finger-piece 51 is depressed by means of the linkage described, the shaft 53 is swung, and the cam-shaped portion 54 actuates upon the fingers 55, to thus force the rolls 14 and 15 away from the driving feed-rolls 16 and 17.

The shaft 22 carries at the end finger-wheels 58 to line-feed the work-sheet independently of the line-space mechanism, 35 which is operatively connected to a ratchet 59, also fast to the shaft 22. Said shaft is laterally located by means of a collar 60 fastened thereto by a set-screw 61.

Variations may be resorted to within the 40 scope of the invention, and portions of the improvements may be used without others.

Having thus described my invention, I claim:

1. In a typewriting machine, the combination with a platen-frame, of a plurality of platens selectively movable to typing position relatively to one another and independently of said platen-frame.

2. In a typewriting machine, the combination with a platen-frame, of a pair of platens movable relatively to each other and independently of the platen-frame, and means common to both platens for controlling their relative positions.

3. In a typewriting machine, in combination, a pair of platens arranged one above the other and movable relatively to each other, and means for causing one of the platens to recede from the printing position as the other platen is moved in front of the receding platen, so as to occupy said printing position.

4. In a typewriting machine, in combination, a pair of platens arranged one above 65 the other and movable relatively to each

other, and means for causing the lower platen to move rearwardly from printing position, to provide room for the upper platen as it descends to said printing position.

70

5. In a typewriting machine, in combination, a double-platen arrangement, and means for transposing the positions thereof, to alternatively move either of the platens to the printing line, said means comprising a hand-operable lever forming an integral part of one of the platens and pivotally mounted upon a supporting shaft, and said lever having cam-slots engaging with pins on the second platen, the latter being fulcrumed at a point adjacent and above the printing point, whereby when one of the platens is brought to the printing point by the swing of the lever, the other platen will be moved away from the printing point, to 85 the rear of the machine.

6. In a typewriting machine, in combination, a pair of platens movable relatively to each other, one of said platens being normally at the printing position and the other 90 platen thereabove, and means for moving the upper platen down to said printing position and for causing the lower platen to move to the rear of the descending platen.

7. In a typewriting machine, the combination with a platen-frame, of a pair of platens movable independently of said platen-frame, one of said platens being movable up or down adjacent the printing line and the other platen being movable in 100 a substantially horizontal plane to and away from said printing line, the first-named platen being effective to shift the horizontally-movable platen away from printing position as said first-named platen 105 moves from an inactive position to said printing position.

8. In a typewriting machine, in combination, a pair of platens movable relatively to each other, one of said platens being movable up or down to dispose said platen at the printing line or removed therefrom, the second platen being laterally movable to and away from said printing line, and means for controlling said first-named platen, 110 said controlling means co-operating with the second platen to determine its position relative to the first-named platen.

9. In a typewriting machine, in combination, a pair of platens movable relatively to each other, whereby either platen may be selectively presented at the typing zone, one of said platens being movable in a substantially horizontal plane to and away from the typing zone, the other platen being movable in an arc up or down relatively to said typing zone, and being normally above the horizontally-movable platen, and means cooperating with both of said platens whereby said horizontally-movable 125

130

platen is shifted to the rear of the other platen when the latter descends to typing position.

10. In a typewriting machine, in combination, a pair of platen-bars movable relatively to each other, one of said bars being movable up and down in an arc adjacent the printing line, the other platen-bar being laterally movable back and forth at said printing line, and means for controlling the relative positions of said platen-bars, so as to selectively present either one of them at said printing line.

11. In a typewriting machine, a pair of platen-bars movable relatively to each other, one of said bars being normally at the printing position and movable rearwardly therefrom, the other platen-bar being movable downwardly from an inactive position to said printing position and effective by such movement to cause the first-named platen to move rearwardly to an inactive position at the rear of said downwardly-movable platen-bar.

12. The combination with a typewriting machine including a revolvably mounted platen-frame, feed-rolls therefor, a platen-frame and means for conducting a work-sheet at the rear of the machine, of a skeleton platen substituting the regular platen, said skeleton platen comprising feed-rolls co-operating with the feed-rolls in the machine for feeding the work-sheet, two platen-strips movable relatively to each other, and means for simultaneously transposing the platen-strips relatively to the printing line.

13. The combination with a typewriting machine including a revolvably mounted platen-frame, feed-rolls therefor, a platen-frame and means for conducting a work-sheet at the rear of the machine, of a skeleton platen substituting the regular platen, said skeleton platen comprising feed-rolls co-operating with the feed-rolls in the machine for feeding the work-sheet, two platen-strips movable relatively to each other, and means for simultaneously transposing the platen-strips relatively to the printing line, said last-mentioned means including a manually-operable handle having cam-slots engaging with pins on one of the platen-strips, whereupon when one of the platen-strips is moved to the printing line, the other platen-strip will be moved away therefrom.

14. In a typewriting machine, in combination, a pair of platens movable relatively to each other to selectively present either of said platens at the printing position, and means for causing one of said platens to move rearwardly from said printing position out of the path of the other platen as it descends from a normally inactive position to said printing position.

15. In a typewriting machine, in combina-

tion, a pair of platen-bars movable relatively to each other, one of said bars being normally at the printing position and movable to a position at the rear thereof, the other platen-bar being normally above the first-named platen-bar and movable downwardly to said printing position, and a handle, associated with the upper platen-bar, for moving it from one position to the other position, said handle including a pin-and-slot connection to the first-named platen-bar effective to cause the latter to recede from the printing position as the upper platen-bar is moved down to said printing position.

16. In a typewriting machine, in combination, a pair of platen-bars movable relatively to each other, feed-rolls for feeding a pack of work-sheets to the printing zone, all of the sheets of said pack being passed over one of said platen-bars, the second platen-bar being effective to split said pack into two sections, the first section passing to the rear of the second-named platen-bar, and the other section over the front thereof, and means for moving said second-named platen-bar down to the printing line and for also causing the first-named platen-bar to recede therefrom, whereby said second-named platen-bar presents only the split portion of said pack at the printing zone, said pack being held stationary by the feed-rolls during such transposition.

17. In a typewriting machine, in combination, a pair of platens movable relatively to each other to selectively bring either one of them to the printing zone or away therefrom, one of said platens being normally at said printing zone and the second platen normally thereabove, feed-rolls for feeding a pack of work-sheets to said printing zone, all of the sheets of said pack passing over the front of the first-named platen, the upper platen being effective to split the pack into two sections, and a lever upon which the upper platen is mounted, said lever being effective to move said upper platen from an inactive position to a position at the printing zone, and including means co-operating with the first-named platen for moving the same away from said printing zone as said upper platen descends, all of the sheets of said pack being held by the feed-rolls during such platen-shifting operation, said upper platen being effective to bring the split section of said pack to said printing zone.

18. In a typewriting machine, the combination of two platen-strips, comprising a lower platen placed at the printing line and an upper platen above the printing line, and means for moving the lower platen away from the printing line simultaneously with the lowering of the upper platen to the printing line, said means including a hand-lever forming an integral part of end-supporting plates, and of the upper platen, and the end.

supporting plates having cam-slots co-operating with a member fast to the lower platen at the ends thereof, the function of the cam-slots being to withdraw the lower platen away from the printing line and to the rear of the machine when the upper platen is lowered by the action of the hand-lever.

19. In a typewriting machine, in combination, a pair of platens movable relatively to each other, one of said platens being normally at the printing zone, the other platen being away from the printing zone, feeding devices for feeding a plurality of sheets to said printing zone, and means for moving the normally effective platen out of the way as the inactive platen is moved into said printing zone, the work-sheets being held stationary by the feed-rolls during such shifting of the platens.

20. In a typewriting machine including a 20 platen-frame, in combination, a pair of platens movable relatively to each other and independently of the platen-frame, one of said platens being suspended from the platen-frame so as to be displaceable in a substantially horizontal plane toward or away from the types, the other platen being mounted upon a lever carried by the platen-frame and being movable thereby, up or down with relation to said types, connections between said 30 lever and the horizontally-movable platen for moving the latter rearwardly away from typing position and for moving the second-named platen into said typing position, and means for limiting the throw of said lever to 35 thereby control the relative positions of said platens.

JESSE A. B. SMITH.
